UNITED STATES PATENT OFFICE.

WILLIAM A. DOBSON, OF BRIDGEPORT, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed November 6, 1925. Serial No. 67,298.

This invention relates to typewriting machines, and more particularly to margin gages and line-locking devices. The invention may be advantageously employed in so-

5 called portable typewriting machines in which durability, cheapness, lightness and compactness are essential.

In practicing the present invention, two stop-levers are pivotally mounted at the rear 10 of the typewriting machine to engage marginal stops on a stop-rod. The stop-lever, which, by engaging the right-hand marginal stop, arrests the leftward movement of the carriage, is yieldingly mounted, and may 15 have a slot in its left end for positively engaging a pendent lever, which in turn moves a bell-crank mounted at the rear and bottom of the machine. From the bell-crank a wire extends forwardly for a connection with a 20 bail, the latter being pulled by the wire against a releasing spring so as to engage under rearwardly-extending cam-bearing lugs pivoted on the key-levers to lock the latter against depression upon typing of the 25 last characters in a line. The keys and carriage may be released by a key which disengages the slotted stop-lever from its marginal stop and permits the releasing spring to swing the bail clear of the lugs.

30 A feature of the present invention is an integral coiled spring element in the wire through which pull is transmitted to the locking bail, whereby the latter after being actuated may be swung to ineffective position because of the yielding of the spring portion, and thus permit the last depressed key-lever to cam the bail aside, rise, and be locked by the bail swinging under its lug.

Another feature is the provision of a 40 flange-and-slot slidable fastening between the two stop-levers, whereby the outer lever, which is compressedly engaged by its associated marginal stop, is braced against side-wise deflection by the inner lever.

45 Other features and advantages will hereinafter appear.

In the accompanying drawings,

Figure 1 is a fragmentary longitudinal sectional view at the center of the machine.

50 Figure 2 is a fragmentary rear elevational view of the machine.

Figure 3 is a perspective view, illustrating the relation of a marginal stop-lever, a sliding stop-lever and certain associated parts 55 to each other.

Figure 4 is a top view, shown partly in section, of the parts illustrated in Figure 2. These parts are seen as one looks down from the front of the machine.

Figure 5 is a fragmentary rear view of 60 the marginal stop-lever in position for operating the line-locking mechanism.

Figure 6 is a fragmentary rear view of the 65 marginal stop-lever in position just after the line-lock-release key has been operated.

Figure 7 is a fragmentary perspective view of the line-lock mechanism and the line-lock-release means.

Figure 8 is an enlarged fragmentary side 70 view of a key-lever locked against depression and a key-lever in depressed position.

Key-levers 10 provided with keys 11, are connected through bell-cranks 11^a and links 12 to type-bars 13 pivoted at 14 and having types 15 arranged to print against a platen 16 upon depression of said keys. The platen may be rotatably mounted on a shaft 18 journaled within bearings, not shown, fast on the ends of a carriage-frame 19, and the latter may be letter-spaced step by step by mechanism usual in such machines. The carriage may have an anti-frictional mounting for step-by-step letter movement, which includes ball-bearing elements 20 in a runway 21 fast to a stiff back plate 22 mounted on the usual shift-frame of the machine. An upwardly-extending apron 24 may be riveted to a lower portion 25 of the runway 21 and have two rearwardly-extending integral lug members 26 and 27, the latter having riveted to it a stud 28 provided with a tapped hole 29.

The travel of the carriage-frame 19 to the right and left may be limited by marginal stops 30 and 31, which may be like those shown and described in the co-pending application of Alfred G. F. Kurowski, Serial No. 715,026, filed May 22, 1924 (now Patent No. 1,572,396, dated February 9, 1926). The marginal stops may be adjustably mounted on a marginal stop-bar 32, the latter being fast on the carriage-frame 19 and having rack-teeth 33 arranged a letter-space distance apart.

To arrest the lateral movement of the carriage-frame 19 at the left end of a line, there is provided a carriage-stop-lever 34 made of sheet-metal, which may have a stop-tooth 35 at the inner or right end (see Figure 2), and a spacing hub 36 at its left end, the hub 100

having a hole 37 engaging around the stud 28. The lever 34 is held by means presently to be described, so that the tooth 35 will engage against and arrest the movement of a 5 lower flange 38 of the stop 30. Means hereinafter described are provided for depressing the stop-lever 34 at will to allow additional travel of the carriage to the right for writing marginal notes and for other purposes.

To stop the leftward movement of the carriage-frame at the right end of the line, there may be provided a sliding stop-lever 40, made of sheet-metal and having a stop-tooth 41 arranged to be compressedly engaged by a lower flange 42 of the marginal stop 31 when the latter has moved near the end of its travel. The lever 40 may have a slot 43 intermediate its ends arranged to engage loosely around a shoulder portion 44 of a screw 45 having a threaded portion 46 arranged for screwing into the threaded hole 29 of the stud 28. A slot 47 may be provided near the inner end of the lever 40 and arranged to engage around a rearwardly-projecting flange 48 on lever 34, which flange may have an open slot 49 arranged parallel with the body of lever 34, the width of the slot 49 being slightly greater than the thickness of the body of the lever 40. When the stop-levers 34 and 40 have been assembled and are in normal position (see Figure 4), they are fastened together near their inner ends by the flange 48 engaging in the slot 47 and by the rim portion of lever 40 around slot 47 engaging in the slot 49, and they are also fastened together at the outer end of lever 34 by the screw 45. The lug member 26 may have a finger 26^a extending to the left and bent out from the body of the apron 24, so as to permit the right end portion of the lever 34 to engage between the finger and apron with a loose sliding fit. A hook 34^a on the right end of the lever 34 may catch under the portion of the lug joining the finger and the apron. By the above-described means, the upward movement of the lever 34 is limited; its ends are held against sidewise deflection; and the lever 40 is slideable relatively to the lever 34 for a purpose hereinafter explained, and is also stiffened or braced by the latter to better resist compression due to the marginal stop flange 42 pressing against tooth 41. A spring 50 normally holds the outer end of the slot 43 against shoulder 44 and the teeth 35 and 41 in position for engaging their associated marginal stops.

60 The flange 42 moving leftwardly strikes a trip finger 51 positioned a short distance to the right of tooth 41, which finger is pivoted on a screw 52 in the outer end of a lateral arm 53 of a bell-crank carrier-lever 54 pivoted about a shoulder-screw 54^a in a

stud 54^b fastened to the apron 24. The finger 51 engages a lug 53^a on the arm 53, and a lower arm 55 of the lever 54 which carries a hammer 56 on a wire 57 is swung counterclockwise causing the hammer to swing up against the action of a coil-spring 58 around the stud 54^b away from a bell 59 mounted on the inner surface of the plate 22. The hammer is swung down against the bell when the flange 42 passes over the finger 51, a slot 60 being provided in the plate to permit movement of the wire 57. This stroke of the bell is the usual signal to the operative that only a few more characters may be typed on that line. Upon the return of the carriage to the right, the flange 42 strikes the finger 51 and swings it idly clockwise against the tension of a restoring spring 61, which may have one end fastened to the lower end of the finger 51, and the other end to an ear 62 on the arm 55. To prevent the carrier-lever 54 from also being swung clockwise, the inner portion of wire 57 is arranged to normally engage against a pin 63 fast in plate 22, which pin also serves to hold one end of the spring 50.

It is desirable to lock the keys 11 against depression upon the actuation of the last type-bar 13 that prints on the line, so that the type-bar may fall back and its key-lever rise and be locked by the same means that locks the remaining key-levers. To this end, a pendent lever 70 is pivoted about a screw 71 in the plate 22 and its upper end 72 fits in a position-holding slot 73 in a flange 74 of the lever 40. The lower end 75 of the lever 70 engages against a rearwardly-extending arm 76 of a bell-crank device 77 pivoted about a vertical screw 78 in a stationary channel-piece 79, the latter being fastened to the frame of the machine. To a leftwardly-extending arm 80 of the bell-crank 77 is fastened a wire 81 which has a coil-spring portion 82 intermediate its ends, and which extends toward the front of the machine to be connected to the rear side of a lower arm member 83 of a locking bail 84, the latter being pivoted above said arm member 83 about screws 85 in bosses 85^a on the frame 23. A spring 86 having one end fastened to a stationary key-lever guide-piece 87 may have its other end fastened to the forward side of the arm member 83 opposite the wire 81. The spring portion 82 of the wire 81 in the normal condition of the machine is stronger than the spring 86, but is without much initial tension, and the spring 86 having more initial tension than the spring 82 normally pulls the lower member 83 of the locking bail over against a pin 87^a fast in the machine-frame, so that the bail stands clear of the key-levers 10.

When the carriage has been moved leftwardly, so as to bring the end of a line to the printing point, the flange 42 will have

engaged with and pushed the slide lever 40 over against the top of the pendent lever 70 (see Figure 5), causing the lower end of the latter to swing the bell-crank device 77 5 clockwise about its pivoted screw 78. This action results in a pull on the wire 81 strong enough to overcome the pull of the spring 86, the latter being weaker than the spring 82, and thus swings the lower portion of the 10 bail 84 rearwardly and an upper cross-piece 88 of the bail forwardly under projecting hook portions 89 of the key-levers 10, which cross-piece locks the latter against depression, as shown in Figure 8. To permit the 15 key of the last character typed to rise and its type-bar 13 to fall back from the platen, the upper side of its hook 89 may have a cam portion at 90, so that pressure of a return spring 91 of its key-lever 10 may cam the 20 cross-piece 88 out of the way, the coil-spring portion 82 of the wire 81 being arranged to yield enough to permit the cross-piece to be swung out a short distance. The latter is then swung back instantly by the spring 82 25 and locks all the key-levers 10 against operation. The employment of the connecting wire 81 arranged with its spring portion 82 is especially advantageous, since it provides a simple, inexpensive, and yielding means 30 for the locking bail that permits the last depressed key-lever to rise and be locked after the bail has been actuated.

It is sometimes required to type a few additional characters to complete a word or 35 syllable after the keys 11 have been locked. This may be accomplished by pressing a line-lock release key 100, which projects from the front of the typewriter frame, and is connected at its back with a small stiff 40 push rod 101, the latter extending rearwardly to a connection with a lower arm 102 of a bell-crank 103 which is pivoted about a pin 104 and has a rearwardly-extending arm 105 arranged to engage under the outer end of 45 the slide lever 40 and raise it (see Figure 6). This swings the inner end of the lever 40 down about the shoulder screw 45, the latter being engaged at that time in the inner end of the slot 43. The tooth 41 is thereby 50 swung down and disengaged from the flange 42, and the spring 50 pulls the slide lever to the right. The pendent lever 70 now has no pulling force on the wire 81 and the spring 86 swings the bail 84 out of locking engagement with the key-levers 10, whose keys 11 may now be operated to type the desired characters. The spring 86 also returns the bell-crank 77 and the pendent lever 70 to normal 55 position. Upon removal of pressure on the release-key 100, a spring 106 coiled around pin 104 restores the bell-crank 103 and its appendages to normal position, and a spring 39 coiled around the hub 36 returns the stop-lever 40 and stop-lever 34 acting in unison 60 therewith to normal position.

To type characters in the usual left-hand margin of a letter, the key 100 may be operated and by co-action of the above-described interponents, the inner end of the slide lever 40 is swung downwards and carries with it 70 the stop-lever 34 because of the flange 48 engaging in the slot 47. The flange 38 may now pass over the tooth 35 permitting the carriage-frame 19 to be moved to the right beyond the usual starting point of a line. The stop teeth 35 and 41 are sloped downwardly at the rear of their working faces, so that the teeth may be pressed down and be ineffective for stopping the flanges 38 and 42, when the latter move over the 75 teeth from their rear.

Variations may be resorted to within the scope of the invention, and portions of the improvements may be used without others.

Having thus described my invention, I 85 claim:

1. In a typewriting machine, the combination with key-levers, a carriage, a marginal stop-rod mounted on said carriage, a marginal stop mounted on said rod, and a pivot on said machine at the rear thereof, of a stop-lever provided with a slot intermediate its ends arranged for engaging around said pivot, said lever being arranged to be engaged at one end by said marginal stop and pushed to the left, and instrumentalities arranged for locking said key-levers, said instrumentalities including a pivoted bail arranged to engage under each of said key-levers to prevent its depression, a lever-system engaging with the other end of said stop-lever from said stop and operable thereby, and a yielding wire connecting said lever-system and said bail whereby to yieldingly hold the latter under said key-levers upon engagement of said marginal stop and said stop-lever, and permit it to be swung temporarily to released position for locking a depressed key-lever.

2. In a typewriting machine, the combination with a carriage, a marginal stop-rod on said carriage, and two marginal stops mounted on said rod, one adjacent each end thereof, of a pivot-member fast on said machine at the rear thereof, a leftwardly-extending lug on the rear of said machine positioned to the right of the pivot, a lever arranged for engaging the left-hand one of said marginal stops and provided with a hole for engaging around the pivot and a finger-member at its right end, the right end portion of said lever being arranged to engage loosely under the outer portion of said lug with the finger engaging under the inner portion of said lug, whereby the upward movement of said lever may be arrested by said lug and the lever may better resist sidewise deflection, a second lever mounted on the pivot outside of said first-named lever and having its right end ar-

ranged to be compressedly engaged by the right-hand one of said marginal stops, and means for fastening said levers together between the pivot and their right ends, where-
5 by said first-named lever may help stiffen said second-named lever against compression from said right-hand marginal stop.

3. In a typewriting machine, the combination with key-levers, a carriage, a marginal stop mounted on said carriage, and a pivot on said machine at the rear thereof, of a stop-lever provided with a slot intermediate its ends arranged for engaging around said pivot, said lever being arranged
10 to be engaged by said marginal stop and pushed to the left, a rearwardly-projecting lug on each of said key-levers arranged adjacent the front of said machine, a bail arranged to engage under said lugs to latch
15 said key-levers against depression, a spring arranged to hold said bail normally out of engagement with said lugs, a bell-crank mounted at the rear of said machine, a pendent lever having its upper end en-
20 gaged by the left end of said stop-lever and its lower end engaging an arm of said bell-crank for rotating the latter about its pivot, and a wire having a tensile spring portion stronger than said bail-holding spring in-
25 termediate its ends arranged for connecting said bell-crank with said bail.

4. In a typewriting machine, the combination with a carriage, a marginal stop-rod on said carriage, and two marginal stops
30 mounted on said rod, one adjacent each end thereof, of a lever provided with a pivotal mounting and having an end engaged by the right-hand one of said stops for arresting the movement of said carriage to the left, and a second lever having its right end arranged for engaging the other of said stops for limiting the movement of said carriage to the right, said second lever being connected at the right of said pivotal
35 mounting with said first-named lever, whereby the latter may better resist the pressure resulting from said stop engaging against it.

5. In a typewriting machine, the combination with a carriage, a marginal stop on said carriage, key-levers, a rearwardly-extending lug on each of said key-levers, and a cam on the upper side of each of said lugs, of a bail having an upper cross-piece mov-
50 able under said lugs and pivoted between said cross-piece and its lower extremities, a spring positioned forward of said bail arranged for holding the same in ineffective position with respect to said lugs, a wire
55 fastened to the lower portion of said bail and extending to the rear of said machine, a spring-coil portion in said wire stronger than said bail-holding spring and being nor-
60 mally without initial tension, and instru-
65 mentalities at the rear of said machine oper-

able by movement of said marginal stop and arranged for exerting a pull on said wire that will move said bail to locking position under said lugs against the pull of said bail-holding spring, said cams being
70 arranged for moving said bail momentarily to ineffective position after it has been actuated, so as to permit a depressed key to rise past said bail and be locked there-
75 after.

6. In a typewriting machine, the combination with a carriage, a marginal stop-rod mounted on said carriage, and a marginal stop adjustably mounted on said rod adjacent each end thereof, of a lever mounted on a pivot fast on said machine and arranged for arresting the movement to the right of the left-hand marginal stop, a second lever mounted on the pivot and having an end arranged for engaging with and arresting the movement to the left of the right-hand marginal stop, said second-named lever having a slot adjacent its stop-engaging end, and a flange on said first-named lever arranged to engage in the slot in said second-named lever, so as to fasten said levers together, whereby the second-named lever may be braced and stiffened by the other lever for better resisting pressure from the marginal stop.

7. In a typewriting machine, the combination with type-printing keys, a carriage, a marginal stop-rod mounted on said carriage, and a marginal stop adjustably mounted on said rod adjacent each end thereof, of a pivot fast on said machine at the rear thereof, a lever mounted on said pivot and extending to the right therefrom and having a tooth at its right end for arresting the movement to the right of the left-hand marginal stop, a flange projecting rearwardly from said lever intermediate said tooth and said pivot and having a slot parallel with the body of said lever, a second lever having a slot intermediate its ends engaging around said pivot and a second slot engaging around said flange, so that the rim of said second slot will engage in the slot in said flange, and a spring arranged for normally pulling said slotted lever to the right, the right end of said slotted lever being arranged to engage with the right-hand one of said marginal stops whereby said slotted lever is moved leftwardly until it is stopped by said pivot.

8. In a typewriting machine, the combination with a carriage, type-printing keys, a marginal stop-rod on said carriage, and two marginal stops fastened on said rod, one adjacent each end thereof, of a stud-member fast on said machine at the rear thereof, a stop-lever having a lateral slot intermediate its ends arranged to engage around the stud and having an open slot in its left end, a spring arranged for normally pulling said lever to the right, a pendent-lever pivoted
120
125
130

intermediate its ends at the rear of said machine arranged for its upper end to engage in the open slot of said stop-lever, and instrumentalities engaged by the lower end of said pendent-lever arranged for locking said keys, the right-hand one of said marginal stops being arranged for engaging the right end of said stop-lever and pushing the latter to the left, thereby swinging said pendent-lever and actuating said instrumentalities, 10 said slot in the end of said stop-lever functioning to prevent sidewise disengagement of said stop-lever and said pendent-lever upon movement of said levers.

15 9. In a typewriting machine, the combination with a carriage, a marginal stop-rod on said carriage, and a marginal stop fastened on said rod adjacent each end thereof, of a pivot, a stop-lever mounted on said pivot and arranged to arrest the lateral movement of the left-hand one of said marginal stops, a second outer stop-lever having a slot engaging around said pivot and having its inner end arranged to be compressedly engaged by the right-hand one of said marginal stops for arresting the lateral movement 25 of the same, means for fastening the inner

portion of said levers together, whereby said outer lever may be braced against compressive strain from said right-hand stop and be movable with respect to said first-named lever, and means for securing the inner end of said first-named lever to decrease its side- 30 wise deflection caused by strain transmitted from the second-named stop-lever.

10. In a typewriting machine, the combination with a carriage and a plurality of key-levers, of a pivoted bail normally clear of said key-levers, a wire fastened to said bail and having a resilient yielding portion, 40 and instrumentalities arranged for automatically pulling on said wire, so as to swing said bail into locking engagement with said key-levers upon a predetermined movement of said carriage, concomitantly with the depression of the last-operated key-lever, said yielding portion of the wire being arranged to permit said bail to be momentarily swung to released position after its actuation by said instrumentalities, whereby the last-operated key-lever may move into position for being locked by said bail.

WILLIAM A. DOBSON.
